US0D1060075S

(12) **United States Design Patent** (10) Patent No.: **US D1,060,075 S**
(45) Date of Patent: ** Feb. 4, 2025

(54) **WEIGHING APPARATUS**

(71) Applicant: **Mettler-Toledo GmbH**, Greifensee (CH)
(72) Inventors: **Fred Held**, Greifensee (CH); **Thilo Hogrebe**, Greifensee (CH); **Sandra Ehrbar**, Greifensee (CH); **Alice Buchmann**, Greifensee (CH); **Michael Meyer**, Greifensee (CH); **Chen Xinghong**, Greifensee (CH); **Wang Heqiao**, Greifensee (CH); **Zhou Mi**, Greifensee (CH); **Xiong Qinghua**, Greifensee (CH)

(73) Assignee: **METTLER-TOLEDO GMBH**, Greifensee (CH)

(**) Term: **15 Years**

(21) Appl. No.: **29/887,569**

(22) Filed: **Mar. 22, 2023**

(51) LOC (15) Cl. 10-04

(57) **CLAIM**

The ornamental design for a weighing apparatus, as shown and described.

DESCRIPTION

FIG. 1 is a bottom view of a weighing apparatus of our new design;

FIG. 2 is a front view thereof;

FIG. 3 is a left side view thereof;

FIG. 4 is a perspective view thereof

FIG. 5 is a rear view thereof;

FIG. 6 is a right side view thereof; and,

FIG. 7 is a top view thereof.

The broken lines shown in the figures are for the purpose of illustrating the environment and form no part of the claimed design.

1 Claim, 7 Drawing Sheets
